UNITED STATES PATENT OFFICE.

HERS EMANUEL M. SCHNÜRER, OF GRUNEWALD, NEAR BERLIN, GERMANY.

APPARATUS FOR TYPE-WRITING AT A DISTANCE.

1,085,496.

Specification of Letters Patent. Patented Jan. 27, 1914.

Application filed April 20, 1911. Serial No. 822,408.

To all whom it may concern:

Be it known that I, HERES EMANUEL M. SCHNÜRER, a citizen of the Kingdom of Roumania, and resident of 16 Hagenstrasse, 5 Grunewald, near Berlin, Germany, have invented certain new and useful Improvements in Apparatus for Type-Writing at a Distance, of which the following is a specification.

10 My invention relates to apparatus for typewriting at a distance, and substantially consists in apparatus which can not only be employed with any typewriting machine and used at any place both as transmitter 15 and as receiver, but when not in use is set for receiving, and whenever any type key is depressed in the transmitter for the time being, a clutch circuit for coupling one part, which is movable at contacts corresponding 20 to the types, with a moved part is closed and, when the movable part arrives on the contact corresponding to the type key which has been depressed, is interrupted. By means 25 of a device, *i. e.* a local relay of the transmitter, set during this coupling and disconnecting operation, the circuit of the long-distance line between the transmitter and receiver is correspondingly closed and opened, and a line relay of the receiver is 30 energized in order to obtain at the receiving station for the time being a uniform and equally long connection or disengagement of the said part movable at contacts with or from the said moved part, so that in the 35 transmitter and receiver the said part movable at contacts makes like movements and remains stationary on the like contact corresponding to the type operated in the transmitter for the time being. The clutch circuit 40 is interrupted in this manner in the transmitter, whereas in the receiver a writing circuit is closed by the local relay of the receiver for electromagnetically depressing that type on which the movable part has re- 45 mained stationary and which is similar to the type actuated in the transmitter.

By pressing the starting type in the transmitter for the time being, contact means which, when not in use, are connected in the 50 writing circuit in order to be able to receive through the machine a character from a distance, are interpolated in the clutch circuit, the driving mechanism of the moved part is driven, by closing a motor circuit, and the 55 local relay is connected into the long-distance line, whereas the line relay is disconnected

from this line. When moving the terminating type of the transmitter, on the contrary, the contact means are switched from the clutch circuit into the writing circuit, the 60 driving mechanism of the moved part is stopped, and the local relay is disconnected from the long-distance line, whereas the line relay is interpolated in this line in order to 65 prepare the machine for receiving.

The line relay of the receiver for the time being, actuated by closing and opening the long-distance circuit through the local relay of the transmitter for the time being, closes and opens not only the clutch circuit of the 70 receiver, but also actuates the driving mechanism of the moved part of the receiver and prepares in the receiver a branch of the writing circuit appertaining to the terminating type, by means of whose excitation the 75 driving mechanism of the moved part and the said branch of the writing circuit in the receiver are stopped and disconnected, respectively, at the termination of the writing operation. Consequently, not only the device in the transmitter, but also that in the receiver is automatically prepared, started 80 working and stopped by the transmitter for the time being, so that no operator is required at the receiving stations. 85

One illustrative embodiment of my invention is diagrammatically represented by way of example in the accompanying drawings, wherein:—

Figures 1, 2 and 3 are side elevation, front 90 elevation and top plan view, respectively, of the apparatus provided at each typewriting machine itself; Fig. 4 is a side elevation, partly in section, showing the type contact disk with pointer, driving gear and clutch, 95 Fig. 5 a front elevation showing a part of the type contact disk, and Fig. 6 shows in projection the position of the tooth of the locking member and of those of the armature relatively to the contact plates of the type 100 contact disk; Fig. 7 is a diagram of the motor battery circuit, Fig. 8 a diagram of the clutch battery circuit, Fig. 9 a diagram of the writing battery circuit, Fig. 10 a diagram of the line battery circuit when the 105 two stations are connected by a long-distance line and the earth, *i. e.* as in telegraphy, Fig. 11 is a diagram of the line battery circuit when the two stations are connected by two long-distance lines, *i. e.* as in telephony, 110 and Fig. 12 is a diagram showing all the circuits.

Similar reference characters indicate the same parts throughout the several figures of the drawings.

In order that the invention may be clearly understood I will first describe in detail in order the principal parts of my apparatus, and subsequently their operation.

The apparatus at the typewriting machine itself, (Figs. 1, 2 and 3.)—Of the typewriting machine itself only those parts are represented which are requisite for understanding the invention and enable the machine to operate as transmitter or receiver in each instance as required. Each key-lever 2, revolute about the common shaft 1, is lengthened by means of a projection or prong 3. The said shaft, key-levers and their prongs are composed of electrically conducting material. The free ends of all the prongs 3 are located in a line parallel to the common shaft 1 and together form a so-called "key-lever comb." In the line of each prong and only a few millimeters from the free end thereof is located the end of another prong 4, a so-called "solenoid prong," all of which are fast on a common rod 5 of insulating material and together form the so-called "solenoid comb," because from each solenoid prong—no such prong belongs to the starting key described hereinafter—a wire 6 leads to the coil of a solenoid 7 arranged under each key-lever 2 with the exception of that of the starting key; the core 8 of each solenoid is electrically non-conductively connected with the appertaining key-lever and when attracted by the energized solenoid depresses its key-lever. This occurs, as more fully explained herein-after, in the typewriting machine acting for the time being as receiver. The other end of each solenoid coil with the exception of that appertaining to the terminating key-lever is connected by a wire 24 with a metallic member 25 common to all the solenoids. The adjacent key-lever prongs 3, on the one hand, and the adjacent solenoid prongs 4, on the other hand, are separated from one another by slabs 9 of insulation. All the slabs 9 are arranged at intervals of 2 to 3 millimeters apart as prongs fast on a revolute rod 10 parallel to the key-lever shaft 1, are preferably connected by distance pins or the like 11 and form the so-called "upper contact comb," because each slab 9 carries in its upper part at both sides a contact plate 12. The contact plates 12 of each slab 9 are insulated from one another, whereas the plates 12 of two adjacent slabs 9 facing one another may be electrically connected together. The lateral edges of the contact plates 12 of each slab 9 do not extend in the position according to Fig. 1 to the ends of the prongs of the key-lever and solenoid combs. When the upper contact comb is rocked, however, a little to the right, as in-

dicated in dotted lines, the plates 12 contact with the ends of the key-lever prongs 3 only, whereas when the upper contact comb rocks to the left its plates 12 contact with the ends of the solenoid comb prongs 4 only. The purpose of this rocking of the upper contact comb toward the key-lever comb and the solenoid comb is to set the typewriting machine in question to transmitting and receiving, respectively. Springs 13 are arranged at both sides on the ends of the key-lever and solenoid comb prongs 3 and 4 in order to assure a good electrical contact of those prongs which are connected in circuit for the time being with the contacts 12. The prongs 14 of the so-called "lower contact comb" project into the spaces between two adjacent slabs 9 of the upper contact comb below the prongs 3 without at any time contacting with the contact plates 12. The prongs 14 of the lower contact comb are composed of electrically conducting material and are electrically connected together, e. g., the entire comb may be cut out of one piece of metal. The lower contact comb is held by screws 15 for example, but can move up and down within small limits about an axis parallel to the shaft 1 and is under the action of springs 16 which admit of this motion relatively to the screws 15 and return the depressed comb into its normal position after the pressure has ceased.

For understanding what follows, the following points regarding the various combs must be borne in mind: Firstly, in the key-lever comb each prong is movable independently of the others downwardly and upwardly about the common shaft 1, and all the prongs are electrically connected together by this shaft. Secondly, in the solenoid comb each prong is immovable, like the comb itself, and insulated from the others. Thirdly, in the upper contact comb the plate-shaped prongs are insulated from one another and not individually movable, but the entire comb can rock. Fourthly, in the lower contact comb in the illustrative embodiment the electrically-connected prongs are not individually movable, but the entire comb is movable downward and upward. Each prong may however be movable by itself and spring-pressed, and may be insulated from the others. Now when any key in the transmitter comprising the upper contact comb in the position shown in dotted lines in Fig. 1 is depressed, the prong 3 of the appertaining key-lever will leave the contact plate 12 of the upper contact comb and contacts with the lower contact comb which is thereby depressed. On the pressure on the key ceasing the key-lever returns into its normal position, when its prong again contacts with the appertaining contact plate 12 of the upper contact comb.

tact comb. The lower contact comb simultaneously returns into its normal position.

On the axle of the upper contact comb is secured at right angles to it and to the central line through the plates 9 a two-armed lever 17, 17' of electrically conducting material. The arm 17' of this lever nearest the key-levers is located within reach of the prong of the starting key A¹, whereas the 10 arm 17 of the lever is within reach of the prong of the terminating key S¹. When the starting key A¹ is depressed the arm 17' is consequently depressed, the upper contact comb is rocked toward the key-levers 15 as shown in dotted lines in Fig. 1, and the typewriting machine is set for transmitting. When the terminating key S¹ is depressed, on the contrary, the upper contact comb is rocked toward the solenoid comb, that is to 20 say the typewriting machine is set for receiving as more particularly described hereinafter. A lever 18, carrying at one end a contact 19, projects at an angle from the lever 17. This contact 19 is wedge-shaped 25 and has one, *e. g.* the upper, half composed of electrically conducting material and the other, *e. g.* the lower, of insulating material (Fig. 1). This contact may be directly on the arm 17 of the lever. At the same time 30 as the arm 17 is depressed, *i. e.* for receiving, the contact 19 operates by entering between two contacts 50 and 51 resting elastically one on the other and presses them apart, the conducting half of the contact 19 remaining, 35 however, electrically connected with the contact 50. In the transmitter, on the contrary, the arm 17' is depressed, and the contact 19 moves away from the contacts 50, 51 which remain electrically connected. The 40 purpose thereof, the connection of the line-relay circuit in a definite manner, is more fully explained hereinafter. In addition, the arm 17' carries a contact 52. When the arm 17' is depressed, *i. e.* when the machine 45 is set as transmitter, the contact 52 contacts with another contact 53 which, as described hereinafter, appertains to the line of the motor-battery main circuit and thereby closes this circuit. If, however, the arm 17 is 50 depressed, the contact 52 breaks the motor-battery main circuit at 53. Obviously, this takes place always after use in all stations, because these are all set to receiving.

The type contact disk with pointer, clutch and locking device for the pointer and driving mechanism of the clutch, (Figs. 4 and 5.)—At each station I provide a disk 20 of non-conducting material, in whose periphery so many embedded contact plates 21 insulated from one another are arranged as the typewriting machine possesses types. Each contact plate 21 is connected by a wire 22 with that contact plate 12 of the upper contact comb which corresponds to the key- 60 lever of the same type-character. When the

pointer 23 rotates its elastic brush 26, which is so broad that it bridges over the gap between two contacts 21 (Fig. 5), slides on the contact plates 21 and before leaving one of the same is electrically connected with 70 the next in the direction of rotation. The pointer 23 must be so mounted on the axle 27, passing through the center of the disk 20, that it does not participate in the axial displacement of the axle when the latter is 75 coupled with its driving mechanism or detached therefrom, because otherwise the brush 26 would not constantly contact with the contacts 21. To this end, in the illustrative embodiment the boss of the pointer 23 is 80 fast on a sleeve 29 which is mounted revolvably, but axially non-displaceably in the frame 35, surrounds the axle 27 and is connected with the latter by means of a key and groove. The pointer 23 may, however, be 85 elastic and directly secured on the axle 27. A compressed coil spring 31 abutting against both the inwardly flanged end of the sleeve 30 and against the enlarged portion 28 of the axle 27 tends to press the latter to the right 90 as seen in Fig. 4, that is to say to draw the armature 32 secured to the one end of the axle 27 toward the disk 20; on the other end of the axle 27 is a disk 33 of electrically non-conducting material, *e. g.* ivory, 95 having a diameter approximately equal to that of the armature 32. The latter forms the one part of an electromagnetic clutch and has on its face a tooth 34 facing the disk 20. Opposite this tooth a rim of like teeth 100 36 for locking or checking the armature is attached on the frame 35. The number of teeth 36 is equal to the number of types in the typewriting machine and these teeth are so arranged relatively to the plates 21 on the 105 disk 20 that the central lines of their gaps exactly coincide with the central lines of the contact plates 21. On the other hand, the tooth 34 is so arranged relatively to the pointer 23 that, when the point of the tooth 110 is located at the deepest part 37 of the individual gaps in the rim of teeth, the central line of the brush 26 is located exactly over the central line of that contact plate 21 which appertains to the gap entered by 115 the tooth 34. This arrangement is for equalizing the unavoidable error in the synchronous rotation of the armature, as will be more fully described hereinafter. Opposite the toothless face of the armature 32 is a pot-shaped magnet 38 which forms the other member of the clutch and is fast on an axle 39 coaxial with the axle 27 and carrying a worm wheel 40 with which meshes a worm 43 keyed on the shaft 41 of the motor 42. 120

Current from the clutch battery II (Fig. 8) can be supplied in the manner described hereinafter to the pot-shaped magnet 38 while it rotates. When this takes place, the armature 32 is attracted, whereby the axle 125 130

27 is coupled with the axle 39 and rotates therewith until the supply of current to the magnet 38 is interrupted and the armature 32 is moved away from the magnet by the 5 spring 31, *i. e.*, the clutch is disengaged. At the same moment the pointer 23 remains with its brush 26 on the contact plate 21 in question. As the point of the tooth 34 of the armature is removed, when the armature 10 is attracted, only the fraction of a millimeter out of the range of the points of the teeth 36, when it begins to move away from the magnet 38 it enters into the gap located at this moment exactly opposite to it and 15 always slides under the action of the spring 31 into its normal position, in which its point is located at the deepest part 37 of the gap.

Against the face of the plate or disk 33 20 nearest the disk 20 lies a small wheel or antifriction roller 44 journaled in the upper arm of a lever 46 pulled by a spring 45 toward the disk 33. The lower end of the lever 46 of electrically conducting material 25 is located in such manner between two elastically mounted contact pins 47, 48 so that when the armature 32 is attracted, the lever 46 moved by the disk 33 moved in the same direction abuts against the pin 48, whereas 30 when the armature is released the lever abuts against the pin 47. Obviously, the lever 46 may be moved by the displacement of the axle 27 in other suitable manner. The parts 33, 44, 45, 46, 47, 48 form a so-called local relay, whose purpose and action 35 are described hereinafter.

The various battery circuits.—To each typewriting machine there belong four different battery circuits: firstly, the circuit of 40 the motor battery I (Fig. 7) which is operative both in the transmitter and in the receiver in order to rotate the two pointers 23 synchronously; secondly, the circuit of the clutch battery II (Fig. 8) which is likewise operative both in the transmitter and 45 in the receiver in order, by simultaneously energizing the pot-shaped magnets 38, to obtain simultaneous engagement of the pointers 23 with the motor shafts 41; thirdly, 50 the circuit of the writing battery III (Fig. 9) which is operative only in the typewriting machine operating for the time being as receiver; and fourthly, the circuit of the line battery IV (Fig. 10) which serves for causing 55 a line relay, more fully described hereinafter, at the receiver to be influenced by the transmitter for the time being and, consequently, for causing the battery circuit of the receiver to be automatically prepared 60 and cut out again after use.

The motor battery circuit, (Fig. 7.)—Current flows from the battery I by way of the feeder 49 to the motor 42 and to the contact 55 33 (Fig. 1) and from here, when the lever arm 17' is depressed, by way of the contact

52 and the feeder 49 connected thereto back to the battery I. If the lever arm 17' is not depressed the motor battery main circuit is open. As this is the case in the receiver, in which the lever arm 17 is depressed, an additional circuit must be provided for each motor battery I, which circuit is disconnected in the transmitter for the time being, in which the main circuit represented in full lines is operative, but is closed, however, in the receiver for the time being by means of the line relay of the receiver to be operated by the transmitter.

The part of the shunt circuit going from battery I to motor 42 is common for transmitting and receiving. The conductor 56 goes from the motor 42 to the contact 57 of the contact lever 58 of the line relay. In the position represented in Fig. 7 this lever is retained by the hook 59 and its contact 57 is prevented from contacting with the contact 60, from which the return conductor 56 goes to the battery I. When the hook 59 releases the lever 58, the spring 61 pulls the latter against the contact 60 and closes the shunt circuit of the motor battery I. The lever 58 of the receiver is released by the transmitter when the line battery circuit is closed, whereupon the electromagnet 62 of the line relay of the receiver is energized and attracts the lever 63 carrying the hook 59. The interruption of the one branch 49 of the motor circuit at the contacts 53, 52 and of the other branch 56 at the contacts 57, 60 allows this motor battery both in the transmitter and in the receiver to rest until the moment of use.

The clutch-battery circuit, (Fig. 8.)—The feeder 64 for the transmitter supplies current from the one pole of the clutch battery II 10 to the pot-shaped magnet 38 (Fig. 4), thence through the axle 27 and the pointer 23 to the brush 26, through the contact plate 21 contacted for the time being by the latter, the wire 22 connecting this plate with the corresponding contact plate 12 of the upper contact comb (Fig. 1), the corresponding prong 3, its key-lever 2 to the common shaft 1. For the sake of clearness, in Fig. 8 the axle 27 is represented a second time out of its 11 proper position which is coaxial with the magnet 38. The feeder 64 connects the other pole of the clutch battery II with the lower contact comb 14. When a key is struck, *i. e.* the lowest in Fig. 8 corresponding to that at the extreme right-hand of the typewriting machine, its prong 3 leaves the appertaining contact plate 12 of the upper contact comb and abuts against the corresponding prong 13 of the lower contact comb. In this manner the main circuit of the clutch battery II of the transmitter is closed by way of all the contact plates 21 of the disk 20 contacted for the time being by the brush 26 with the ex- 120

ception of that contact plate 21 corresponding to the depressed key-lever 2, that is to say, the current flows from the battery II through feeder 64, magnet 38, axle 27, pointer 23, the contact plate 21 contacted for the time being by the brush 26, wire 22, contact plate 12 of the upper contact comb, prong 3, key-lever 2 to the common shaft 1, and thence by way of the depressed key-lever 2 and the prong 14 of the lower contact comb contacted by this key-lever back to the battery II. Consequently, when a key-lever is depressed, the pot-shaped magnet 38 is energized and the pointer 23 thrown into engagement with the motor shaft 41. The pointer consequently rotates over the contact plates 21 until it contacts only with that one whose upper contact plate 12 is not connected with the axle owing to the key-lever 2 being depressed. At this moment the main circuit of the clutch battery is opened, the magnet 38 no longer energized releases its armature 32 which is at once locked by the teeth 36 and retains the pointer 23 on the contact plate 21 in question corresponding to the depressed key-lever. When the latter is released it moves away from the prong 14 of the lower contact comb, consequently breaks the connection between the latter and the shaft 1 of the upper contact comb, and with its prong 3 connects its contact plate 12 and the shaft 1, and thus prepares this connection for the passage of the pointer 23 when another key-lever is depressed. The depression of a key-lever 2 consequently fulfils two duties in the transmitter: it closes the main circuit of the clutch battery for coupling the pointer 23, but breaks this connection at that contact plate 12 which corresponds to the depressed key-lever and thus to the contact plate 21 on which the brush 26 is to remain stationary. This operation is repeated whenever any key-lever is depressed in the transmitter. The pointer 23 of the receiver must move exactly in the same manner, *i. e.* synchronously, as long as the pointer 23 of the transmitter moves, and its brush 26 must remain stationary on that contact plate 21 of its disk 20 which corresponds to that contact plate 21 of the disk 20 of the transmitter, on which the brush 26 of the transmitter remains stationary, in order that the corresponding key-lever possessing the same type may be depressed in the receiver by means of the hereinafter described writing battery circuit. Now as each station is to be usable both as transmitter and as receiver, but as in the receiver the magnet 38 cannot be energized by its clutch battery main circuit for the purpose of coupling the armature 32 and with it the pointer 23 with the motor shaft 41, because in the receiver the upper contact comb and its contact plates 12 are moved away from the key-lever prongs 3, I provide for the circuit of the clutch bat-

tery an additional branch which becomes operative for the time being only in the receiver, in order to be able to energize the magnet 38 of the receiver corresponding to that of the transmitter by means of the latter. To this end, a conductor 65 connected to that pole of the battery II which is connected with the lower contact comb 14 leads to the fulcrum of the lever 63 (mentioned above in the description of the motor circuit) whose contact 55 is normally prevented by a spring 66 from contacting with a contact 67, from which the conductor 65' leads to the magnet 38 and from the latter, by way of the part of the line 64 common for transmitting and receiving, to the other pole of the battery II. This second branch of the clutch battery circuit comprising the conductor 65 must be interrupted when the station in question operates as transmitter, because otherwise the pot-shaped magnet 38 would be constantly energized and the transmitter pointer would continuously rotate when the motor 42 started.

When the station is to operate as receiver, 90 the lever 63 is attracted by the electromagnet 62 of the line relay energized in the manner described hereinafter, and the clutch shunt-circuit of the receiver is closed owing to the contact 55 of the lever 63 contacting 95 with the contact 67. Consequently, by correspondingly energizing the line relay of the receiver by means of the transmitter, the clutch shunt-circuit 65 in the receiver can be opened and closed corresponding to the 100 clutch main circuit of the transmitter, that is to say the pot-shaped magnets 38 of both stations can be simultaneously energized or kept currentless and the clutch battery II in the receiver can be automatically cut out of 105 circuit after use. The interruption of the clutch shunt-circuit at the contact 67 thus serves in the transmitter for the time being for disconnecting the conductor 65 entirely, but, in the receiver, for disconnecting the 110 magnet 38 from the armature 32, independently of the movement of the key-levers, whenever in the transmitter the supply of current to the magnet 38 is stopped. When the branch circuit of the receiver is closed 115 between two successive interruptions of the branch 65 at the contact 67, the magnet 38 of the receiver is each time energized by the transmitter simultaneously with that of the transmitter. As mentioned above, each 120 lower contact comb prong may be insulated from the others. In this event, each must be connected by a conductor 64 with the battery II.

The writing battery circuit, (Fig. 9.)— 125 The circuit of the writing battery III operates for the time being only when receiving. To this end, the contact plates 12 are moved away from the prongs 3, by tilting the upper contact comb, and contact with 130

the prongs 4 of the solenoid comb. As mentioned above, each of the latter prongs is connected by a wire 6 with a solenoid 7 (Fig. 1) under the key-levers. The wires 24 going from these solenoids, with the exception of that of the terminating key, unite, as mentioned above, in one common metal member 25, from which a feeder 68 leads to one pole of the battery III. The feeder 68 leads from the other pole of this battery to the fulcrum of the lever 46 of the local relay (Fig. 4). Current in the feeder 68 attached to the contact 47, against which the lever 46 rests when the armature 32 is not attracted, flows by way of the axle 27, pointer 23, brush 26, contact plate 21 on which the brush is stationary, wire 22 to the corresponding contact plate 12 of the upper contact comb, to the appertaining prong 4 of the solenoid comb, wire 24, metal member 25 to the battery II. Consequently, that solenoid 7 is energized, for the purpose of depressing the appertaining key-lever 2, on whose contact plate 21 the brush 26 remains stationary, when the armature 32 is released, and is connected into the circuit 68. If the brush 26 remains stationary on the contact plate 21 corresponding to the terminating key S¹, the circuit goes from the solenoid 7 of the terminating key to another electromagnet 69 of the line relay (Fig. 7), thence to the fulcrum of the lever 58, the arm of the latter carrying the contact 54 which, when the lever 58 is released by the hook 59, contacts with a contact 70, and from the latter by way of feeder 71 back to the battery III. As soon as the armature 32 is attracted by the magnet 38 owing to the action of the clutch circuit, the lever 46 is released from the contact 47, so that the writing circuit is interrupted. In the transmitter, the contacting of the contact 47 by the lever 46 of the local relay is unaccompanied by any action, because in the transmitter the upper contact comb is not in contact with the solenoid comb and consequently the writing battery III is disconnected. Consequently in the transmitter, the local relay has only the one, but exceedingly important purpose of bringing the lever 46 into contact with the contact 48 of the line-relay circuit whenever the armature 32 is attracted, in order to negative the breaking of this circuit in the transmitter only whenever a key is depressed and to close the circuit again after the release of a key, in other words to influence the line relay of the receiver correspondingly. In the receiver, on the contrary, the local relay operates solely for closing and breaking the writing battery circuit at the contact 47. These operations of the local relay in the transmitter on the one hand and in the receiver on the other hand

will be more clearly understood from the following description.

The line relay and its circuit, (Fig. 10.)— The arrangement of the parts of the line relay relative to the various battery circuits has been described above when describing these circuits. Consequently, it is only necessary to give a short recapitulation of all those separate parts, in order to explain the entire construction and the connection of the circuit. As only the line relay of the typewriting machine operative for the time being as receiver is actuated and controlled by the local relay of the transmitter, in order to close and open the clutch circuit of the receiver corresponding to that of the transmitter, the connection of the line-relay circuit must be such that the line relay of the transmitter for the time being is disconnected, its local relay however connected in circuit, while the local relay of the receiver for the time being is without influence on the line relay circuit, i. e. is disconnected, whereas the line relay is connected in circuit. The local relay must be located in the line-relay circuit because the machine operates sometimes as transmitter and at other times as receiver.

When the electromagnet 62 of the line relay of the receiver interpolated in the line-relay circuit becomes energized, the armature arm 63 is attracted and closes the branch 65 of the clutch circuit at 67; the hook 59 of the arm 63 simultaneously releases the lever 58 which is brought by the spring 61 on the one hand into contact with the contact 60 and thereby closes the branch 56 of the motor circuit at the receiver and, on the other hand, rests against the contact 70 and thereby prepares the terminating-key branch 71 of the writing circuit in order that when the branch 26 remains stationary on that contact plate 21 which is connected in this branch and corresponds to the terminating key, the electromagnet 69 may be energized, attract the lever 58 and thereby interrupt the motor shunt-circuit. As soon as the electromagnet 62 becomes currentless, which occurs whenever the local relay lever 46 of the transmitter is moved away from the contact 48, that is to say when the armature 32 of the transmitter is released by its magnet 38, the armature arm 63 returns into its rest position and thereby opens the clutch shunt-circuit in the receiver. The motor shunt-circuit and the writing circuit of the receiver, however, remain connected until the electromagnet 69 is also energized and the lever 58 snaps behind the beveled head 59. This takes place only when the terminating key is depressed. The connection of the line-relay circuit varies according as one wire and the earth, as in telegraphy, or two wires, as in telephony, are

utilized for connecting the stations or, lastly, as means for wireless transmission are employed.

In the telegraphic connection the connection (Fig. 10) is as follows: In the transmitter, the lever 17 is so placed that the contact 19 is in an inoperative position, *i. e.* away from the contacts 50, 51. This position of the lever is obtained when the clutch main circuit is closed and the writing circuit opened. The elastic contacts 50, 51 contact one another. In the receiver, on the contrary, the lever 17 is in its operative position when its contact 19 is between the contacts 50, 51 and has moved them apart. In this event, however, the contact 19 has its conducting half against contact 50, so that the lever 18 is connected by way of the connecting wire 72 of the two contacts 50 and by way of the contact 19 with the wire 73 which leads by way of the electromagnet 62 of the line relay of the receiver to earth at E. In the transmitter, the conductor 73 of the line relay is of course likewise earthed, namely in the illustrative embodiment at e. From each contact 51 a wire 74 leads to the contact 48 of the local relay, and from the fulcrum of the lever 46 of this relay to one pole of a line battery IV whose other pole is earthed at the receiver at E' and in the transmitter at e. Current cannot flow from earth E to earth E' because, even when the lever 46 of the local relay of the receiver is attracted, *i. e.* connects the two parts of the conductor 74 at 48, the insulated part of the contact 19 prevents an electrical connection being established between the contacts 51 and 50. The local relay of the receiver is thus disconnected from the line-relay circuit. Current cannot however flow from earth E to earth e' because in the transmitter the contact 19 has swung away from the contact 50. Consequently, the line relay of the transmitter is disconnected from the line-relay circuit. On the other hand, whenever in the transmitter the armature 32 is attracted by the magnet 38 and drives the lever 46 of the local relay against the contact 48, current can flow from earth E to earth e', battery IV, conductor 74, contacts 50, 51 in the transmitter, line 72, contact 50 in the receiver, conductor 73 and back to earth E. Consequently, the line relay of the receiver is connected by way of the local relay of the transmitter into the line-relay circuit.

It will be readily understood that when the parts played by the transmitter and receiver are to be exchanged, by introducing the left-hand contact 19 in Fig. 10 between the contacts 50, 51 and by removing the right-hand contact 19 in Fig. 10 from the contacts 50, 51 a path for the current of the line-relay circuit is prepared from earth e to earth E', namely from the one pole of the right-hand battery IV in Fig. 10 by way of

conductor 74, lever 46, contact 48, conductor 74, contacts 51, 50 (right-hand), line 72, contact 50 (left-hand), contact 19, lever arm 18, conductor 73, earth e, earth E' to the other pole of the battery IV. In Fig. 10, 70 the line 72 marked with cross strokes is operative in any event, and the dotted lines show the disconnected, and the full lines the connected, *i. e.* operative, branches of the circuit. In the event of transmitter and receiver changing the parts played by them, the conductors represented in full lines become inoperative and those represented in dotted lines become operative.

When two stations are connected as in telephony the connection is similar to that just described, but in this event the earthing of each line battery and of each line relay is omitted. Instead thereof, the pole in question of the line battery and the wire 73 of the line relay of each station is connected with a contact 75, and the contacts 75 are connected by the second long-distance line 76, as shown in Fig. 11. In the case of wireless connection, the two stations must be provided with the requisite transmitting and receiving apparatuses.

My apparatus operates as follows: When not in use, all the typewriting machines arranged in the above described manner are set to receiving in order that any desired typewriting machine can be operated, without the aid of an operator, by any other individual machine, if necessary after connection by means of a central station or exchange for writing at a distance. In order to bring this about, *i. e.* to be able to use the machine as transmitter, by depressing the starting key A¹ the upper contact comb is tilted over toward the prongs 3. The upper contacts 12 contact with the latter; the lever arm 17' is depressed and closes in the transmitter the motor circuit at the contacts 52, 53. The motor commences to rotate and rotates the magnet 38. At the same time as the lever 17, 17', is rocked, the contact 19 is removed from the contacts 50, 51. the line relay in the transmitter is consequently disconnected from the line-battery circuit, the local relay on the contrary is connected into this circuit, so that the line-relay of the receiver is connected by way of the local relay of the transmitter in the circuit of the line battery. (Figs. 10 and 11). By depressing the starting key and in consequence of the other keys requisite for writing at a distance being depressed, the prongs 3 of the latter contact with the lower contact comb 14 whereby the clutch battery is connected in circuit. (Fig. 8). The rotating magnet 38 of the transmitter thus becomes energized and attracts its armature 32 which also rotates and rotates the pointer 23 whose brush consequently slides on the contacts 21 of the disk 20. Owing to the arma-

ture 32 being attracted, the lever 46 of the local relay of the transmitter closes the line-relay circuit broken at this place only (Figs. 10 and 11 full lines); the electromagnet 62 of the line relay of the receiver is consequently energized and attracts the lever 63, whose head 59 releases the lever 58. Under the influence of the spring 61, the lever 58 closes the branch 56 of the motor circuit of the receiver at the contacts 57, 60, and also the contact 54 of this lever closes at the contact 70 the terminating-key branch 71 of the writing circuit of the receiver, while the contact 55 of the arm 63 closes at the contact 67 the branch 65 of the clutch circuit in the receiver. Owing to the motor shunt-circuit of the receiver being closed its motor and its magnet 38 rotate. By closing the clutch battery shunt-circuit of the receiver in sequence of a key being depressed at any time, the magnet 38 of the receiver is energized, attracts its armature 32 and rotates the pointer 23 with its brush 26 over the contact plates 21.

25 As described above in the detailed description of the clutch circuit, when writing on the transmitter machine, as soon as the brush 26 arrives at that contact plate 21 which corresponds to the depressed key, the clutch circuit is broken, and the armature 32 is released by the pot-shaped magnet and at once locked. The brush 26 of the transmitter therefore remains stationary on the contact plate corresponding to the depressed key. In the receiver, however, the brush 26 must also remain stationary on that contact plate 21 which corresponds to the key to be depressed which, on its part, must be identical with that depressed in the transmitter. 30 This is brought about by the lever 46 of the local relay of the transmitter moving away from the contact 48 of the line-relay circuit, when the armature 32 is released in the transmitter, and breaking this circuit. The electromagnet 62 of the line relay of the receiver thereby becomes currentless and the spring 66 pulls the arm 63 into its rest position, when the contact 55 is removed from the contact 67 and interrupts the clutch circuit of the receiver. Consequently, the pot-shaped magnet 38 of the receiver is also rendered currentless and releases its armature 32 which is at once locked, so that the brush 26 remains stationary on the same contact plate 21 as in the transmitter.

35 While the armature 32 of the receiver is being locked, the disk 33 of the local relay of the receiver releases the lever 46 which, pulled by the spring 45, contacts with the contact 47, whereby the writing circuit in the receiver is closed by way of that contact plate 21, on which the brush 26 has remained stationary. The solenoid 7 under the corresponding key-lever becomes energized and 40 attracts its core 8 and the key-lever. The

typewriting machine of the receiver consequently prints that type, whose key has been depressed in the transmitter. The starting key A¹ has no solenoid 7 because otherwise, when depressing the same in the transmitter, it would be depressed also in the receiver, which must not occur because otherwise the starting key-lever of the receiver would press on the lever 17, 17', that is to say would tilt over the upper contact 70 comb toward the key-lever prongs 3 and thereby set the machine occupied in receiving to transmitting. Obviously, in the transmitter the key-lever must remain depressed at least until the brush 26 has arrived at the corresponding contact plate, because otherwise the clutch main circuit of the transmitter would be broken at the lower contact comb 14, the pot-shaped magnet 38 would consequently become currentless too 75 soon and the brush 26 would remain stationary on an incorrect contact plate 21. Likewise, the prematurely operating local relay of the transmitter would disconnect the line-relay of the receiver too soon, so that the clutch shunt-circuit would be prematurely interrupted there also and an incorrect type would be written. When high speed motors are used, however, the time required by the brush for traversing the longest distance, rather less than a complete circle, is 80 very short.

85 It is assumed that the two motors in the transmitter and receiver run synchronously, and consequently that the two brushes 26 move synchronously, because they simultaneously begin to slide from the same places, describe equal arcs and cease moving simultaneously. Consequently, they will always remain stationary on the contact plates 21 which correspond to the same characters. Now, as is well-known, perfectly synchronous rotation of two like electric motors cannot be obtained, and in consequence of the inequality 90 of the pointers 23 in the transmitter and receiver would not describe equal arcs in unit time, and therefore would not remain stationary on the same contact plates 21. The apparatus would consequently be unusable. This disadvantageous influence of the unavoidable inequality in the speeds of the motors is here negated, however, by the above-described armature locking-device. As 95 mentioned above, when the rotating brush 26 is stopped it remains with its center over the middle line of that contact plate 21 which is opposite the tooth gap entered by the tooth 34 at the moment of the pot-shaped magnet 38 becoming currentless, and the point of the tooth 34 is then located at the deepest part 37 of this gap. The pot-shaped magnet 38 becomes currentless in the transmitter as soon as the brush 26 contacts with the contact plate corresponding to the depressed key. Now if for the various typewriting ma- 100

105 110 115 120 125 130

chines belonging to one central station or exchange motors are employed whose speeds fluctuate between 1985 and 2015 revolutions per minute, and consequently have at most 5 a difference of 30 revolutions per 2000=1½% revolutions per minute, and if this difference per cent. per minute is at most not more than half the breadth of one contact plate in degrees relatively to 360 degrees, *e. g.*, in the 10 case of thirty-six contacts each=10°, the half=5°, *i. e.* about 1½% of 360°, unequal arcs of the brushes in the transmitter and receiver are automatically equalized into 15 equally long arcs when the brushes remain stationary.

The arc described by the brush 26 of the transmitter in no case embraces more than thirty-five contact plates 21, thus at most 360°. The arc described by the brush of 20 the receiver is at most 1½% larger or smaller. In the transmitter, the armature 32 of the pot-shaped magnet 38 is released and drawn away by the spring 31 as soon as the brush 26 contacts with the contact plate 21 corresponding to the depressed key, the point of the tooth 34 arrives into the middle line of the tooth gap and the middle of the brush is on the middle of this contact plate. (Fig. 6). As the arc described by the point of the 25 tooth 34 in the receiver is at most 1½% in degrees larger or smaller than that described by the point of the tooth of the receiver, the point of the tooth of the receiver will be located to the right or left of the middle line 30 of that tooth gap which corresponds to the contact plate of like designation. But as this deviation to the right or left is less than half the distance between the two locking teeth 36 of the tooth gap, however, as soon 35 as the armature 32 is retracted from the pot-shaped magnet the point of the tooth 34 in the receiver will always enter into the tooth gap analogous to that in the transmitter. The point of the tooth 34 must, however, 40 always arrive at the deepest part 37 of the tooth gap, and consequently, in the receiver the brush 26 remains stationary with its middle over the middle line of the contact plate 21 in question, that is to say 45 both the brushes always describe equal arcs and always start from corresponding places. After the brush 26 in the transmitter has once arrived at that contact plate 21 which corresponds to the depressed key, the release 50 and upward motion of the key-lever causes the prong 3 to contact with its upper contact 55 12 in order to connect that plate 21 electrically with the shaft 1, on which the brush 26 had previously remained stationary, when another key is depressed and the brush 26 rotates.

When writing at a distance is finished, the terminating key S¹ in the transmitter is depressed, whereby the upper contact comb is 60 tilted over toward the solenoid comb and

the machine is set ready for receiving. Before this occurs, however, as the last step but one the terminating key of the receiver is drawn downward in like manner as in the case of the other keys and indicates the termination of the writing from a distance for the time being. The electromagnet 69 (Fig. 9) is energized and attracts the lever 58 which passes the slanting head of the line-relay lever 63, slightly raising the same, and breaks the motor shunt-circuit between the contacts 57 and 60, and also breaks the terminating-key branch of the writing circuit in the receiver between the contacts 54 and 70. The clutch shunt-circuit has shortly before been opened by interrupting the line-relay circuit by means of the local relay of the transmitter. Consequently, in the machine which has been used as receiver all the batteries I to III remain at rest, and battery IV in the receiver is also disconnected. In the transmitter, owing to the upper contact comb being tilted this comb moves out of the range of the key-lever prongs 3, so that the circuit of the clutch battery II cannot be closed by way of them. Also, the contact 52 moves away from the contact 53, so that the motor main-circuit is broken, and, lastly, the contact 19 enters between the contacts 50, 51 in order to place the line battery IV of the transmitter at rest and to prepare the long-distance circuit for the line relay of the former transmitter for influencing any other station from the local relay. Consequently no assistance of any operator is required, but all the circuits are connected and disconnected and the parts for writing at a distance are moved completely automatically by the transmitter.

In conclusion it may be explained how the unavoidable delay in the attraction of the armature 32 or of the line-relay lever 63 of the receiver relatively to that of the like parts in the transmitter is equalized, in order to overcome the non-synchronous motion of the brushes 26 occurring owing to both this uneven operation of the said parts and the retarded starting of the motor of the receiver. This is brought about by the contacts 48 in the local relay and 55 in the line relay being sliding contacts or, as shown in Fig. 4, bush contacts, *i. e.* contacts which, after they have been contacted by the lever coacting with them, follow the motion of the lever within certain limits in both directions. These limits are determined by the following formula:—

$$x^1 + b + c = x + a + c^1$$

when x^1 designates the period during which the brush of the receiver runs; x the period during which the brush of the transmitter runs; b the time during which the armature 32 when attracted by the pot-shaped magnet runs toward the latter without the lever 46 130.

contacting with its contact; c the time during which the lever 63 of the line relay moves under the action of the electromagnet 62 without contacting its contact; a the time 5 during which the armature 32 is withdrawn by the spring 31 from the magnet 38 while the lever 46 is making contact, and, lastly, c^1 the time during which the lever 63 of the line relay is drawn away by the spring 66 10 from the electromagnet 62 while making contact. The value c^1 may, in certain cases, be zero. As the arcs which the brush 26 of the transmitter traverses during the time x and that of the receiver during the time x^1 15 should be equal, the time x and x^1 must also be equal. Consequently, in the formula $b+c$ on the one hand and also $a+c^1$ must be equal. This is most readily obtained when the time a is made equal to b and the time c 20 equal to c^1 .

In order that the times a and b may be equal, the paths traversed in the ~~same~~ by the lever 46 must be unequal, to wit the path traversed in the time b must be greater than 25 the path traversed in the time a , because the path traversed in the time b takes place under the attraction of the pot-shaped magnet 38 which is necessarily stronger than the tensile force of the spring 31, under 30 whose action the path traversed in the time a takes place. For the same reason, the path traversed in the time c must be greater than that in the time c^1 in order that the times c and c^1 may be equal. In order that the arcs 35 described in the times x and x^1 may be equal, i. e. the time a equal to b and the time c equal to c^1 , I proceed as follows: The tensile forces of the springs 31 and 66 are selected as little as possible less than the at- 40 tractive forces of the electromagnets 38 and 62, respectively. The paths traversed during the times a and b are then made equal, and the pot-shaped magnet 38 of the receiver is connected into circuit directly by 45 way of the local relay of the transmitter. It is seen that x^1 is greater than x . This proves that the time a or the path traversed during the same is too great. Therefore a is very gradually diminished until $x^1=x$. The 50 magnet 38 of the receiver is then connected into circuit by way of the line relay of the receiver and the latter by way of the local relay of the transmitter. It is now found that the arc described in the time x^1 is again 55 greater than that described in the time x which proves that the time $b+c$ is smaller than the time $a+c^1$ and that, as b , is equal to a , the time c is shorter than c^1 . Now in order that the times c and c^1 may be equal, 60 the path traversed in the time c must be increased. This takes place quite gradually until the arc for the time x^1 is equal to the arc for the time x . The time c is now also equal to the time c^1 , because the path trav-

ersed in the time c is greater than that trav- 65 ersed in the time c^1 .

It is to be understood that nothing herein contained is to be construed as limiting my invention in the scope of its application to use in connection with the particular apparatus or particular mode of operation, or both, selected for the purposes of illustration and explanation.

While the particulars of construction and arrangement herein set forth are well suited to one form of the invention, it is not to be understood that these particulars are essential since they may be variously modified within the skill of the artisan without departing from the true scope of the actual 75 invention as defined in the following claims.

I claim:—

1. Apparatus usable both as transmitter and as receiver for intercourse between typewriting machines at a distance, comprising at each station a driving means, a part driven thereby, stationary contacts corresponding in number to the type keys, a part movable over said stationary contacts, an electrically operated clutch mechanism for coupling and disengaging said two parts at the receiver uniformly and for an equally long time as at the transmitter, an electric circuit including said types, said clutch mechanism, said movable part and 85 said stationary contacts, contacts operated at the transmitter by actuating a key for closing and interrupting said clutch circuit, a line circuit connecting the transmitter and receiver, a contact member operated by 90 the coupling and disengaging movements of said movable part at the transmitter for closing and interrupting said line circuit, a contact means in the clutch circuit moved at the receiver by operating said line-cir- 95 cuit for closing and interrupting said clutch-circuit simultaneously and analogously as at the transmitter and means elec- 100 trically operated by said contact member at the receiver for actuating the key corre- 105 sponding to that actuated at the transmitter.

2. Apparatus usable both as transmitter and as receiver for intercourse between typewriting machines at a distance, comprising at each station a driving means, a 115 part driven thereby, stationary contacts corresponding in number to the type keys all of which are electrically connected, a part movable over said stationary contacts, an electrically operated clutch mechanism for 120 coupling and disengaging said two parts at the receiver uniformly and for an equally long time as at the transmitter, an electric circuit including said keys, said clutch mechanism, said movable part, said station- 125 ary contacts and an equal number of contacts connected therewith being touched at the transmitter by the type keys only when

they are not actuated, a contact in the path of each key touched by actuating a key for closing at the transmitter said clutch circuit which is automatically interrupted, 5 when the movable part arrives at that stationary contact, which corresponds to and is out of connection with the actuated key, a line circuit connecting the transmitter and receiver, a contact member operated by the 10 coupling and disengaging movements of said movable part at the transmitter for closing and interrupting said line circuit, a contact means in said clutch circuit moved at the receiver by operating said line circuit for closing and interrupting said clutch circuit simultaneously and analogously as at the transmitter and means electrically operated by said contact member at the receiver for actuating the type key corresponding 15 to that actuated at the transmitter.

3. Apparatus usable both as transmitter and as receiver for intercourse between typewriting machines at a distance, comprising at each station an electromotor, a motor 25 battery circuit, a part driven by said electromotor when its circuit is closed, stationary contacts corresponding in number to the type keys, contact means each electrically connected with one of said stationary contacts and adapted to be brought in contact at the transmitter with the corresponding type key in its not actuated position, all keys being electrically connected, a part movable over said stationary contacts, an 30 electrically operated clutch mechanism for coupling and disengaging said two parts at the receiver uniformly and for an equally long time as at the transmitter, an electric clutch circuit, a contact in the path of each key, touched by actuating a key for closing at the transmitter said clutch circuit, which is automatically interrupted when said movable part arrives at that stationary contact corresponding to and being out of connection with the actuated key, a line circuit connecting the transmitter and receiver, a contact member operated by the coupling and disengaging movements of said movable part at the transmitter for closing and 45 breaking said line circuit, a contact means in said clutch circuit moved at the receiver by operating said line circuit for closing and interrupting said clutch circuit simultaneously and analogously as at the transmitter and means electrically operated by said contact member at the receiver for actuating the type key corresponding to that which is actuated at the transmitter.

4. Apparatus usable both as transmitter and as receiver for intercourse between typewriting machines at a distance, comprising at each station an electromotor, a motor battery circuit, a part moved by said electromotor when its circuit is closed, stationary contacts corresponding in number to the

type keys, contact means each electrically connected with one of said stationary contacts and adapted to be brought in contact at the transmitter with the corresponding type key in its not actuated position, a contact in the path of each actuated key, a part movable over said stationary contacts, an electrically operated clutch mechanism for coupling and disengaging said two parts, a clutch circuit for said coupling means operated at the transmitter by actuating a key, a contact member actuated by the coupling movements of the movable part for closing at the transmitter a line circuit connecting the transmitter and receiver including a line-relay, a contact means in the clutch circuit moved at the receiver by said line relay for operating the clutch mechanism at the receiver uniformly and for an equally long time as at the transmitter and means electrically operated at the receiver by said contact member for actuating the type key corresponding to that which is actuated at the transmitter, the motor battery circuit having two branches, a main branch with a contact operated at the transmitter for closing said main branch at the starting and for interrupting at the end of the working and an additional branch with a contact held in interrupting position at the transmitter, the circuit of the line relay at the transmitter being interrupted by a contact means moved apart, while at the receiver the contact of the main branch of the motor battery circuit is in interrupting position and the contact of the additional branch is released by the line relay of the receiver, whose circuit is closed at the transmitter by the contact member being operated at the first coupling of the movable part with the moved part.

5. Apparatus usable both as transmitter and as receiver for intercourse between typewriting machines at a distance, comprising at each station an electromotor, a motor battery circuit having two branches with contacts, a part moved by said electromotor when said branches are closed, stationary contacts corresponding in number to the type keys, a part movable over said stationary contacts, an electrically operated clutch mechanism for coupling and disengaging said two parts, a clutch circuit operated at the transmitter by actuating a key, a contact member operated by the coupling and disengaging movements of said movable part, a line circuit connecting the transmitter and receiver and operated at the transmitter by said contact member, a line relay in said line circuit, a contact means in said clutch circuit moved at the receiver by operating said line relay for actuating the clutch mechanism uniformly as at the transmitter, means electrically operated by said contact member at the receiver for actuating the same key as at the transmitter, an independent

- ent starting key actuated only at the transmitter, and a finish key arranged as all the type keys and actuated at the transmitter, at the end of the transmitting, to prepare the station as receiver, the contact in the main branch of the motor circuit being arranged to be closed by actuating said starting key and to be placed in interrupted position by actuation of said finish key.
10. Apparatus usable both as transmitter and as receiver for intercourse between typewriting machines at a distance, comprising at each station an electromotor, a motor battery circuit having two branches with contacts, a part moved by said electromotor when said branches are closed, stationary contacts corresponding in number to the type keys, a part movable over said stationary contacts, an electrically operated clutch mechanism for coupling and disengaging said two parts, a clutch circuit operated at the transmitter by actuating a key, a contact member operated by the coupling and disengaging movements of said movable part, 20 a line circuit connecting the transmitter and receiver and operated at the transmitter by said contact member, a line relay in said line circuit, a contact means in said clutch circuit moved at the receiver by operating said line relay for actuating the clutch mechanism uniformly as at the transmitter, means electrically operated by said contact member at the receiver for actuating the same key as at the transmitter, an independent starting key actuated only at the transmitter, and a finish key arranged as all the type keys and actuated at the transmitter at the end of the transmitting to prepare the station as receiver, the contact in the main branch of the motor circuit being arranged to be closed by actuating said starting key and to be placed in interrupted position by actuation of said finish key, a line circuit contact which is moved at the transmitter in interrupting position by actuating the starting key and at the receiver in closing position by actuating the finish key.
7. Apparatus usable both as transmitter and as receiver for intercourse between typewriting machines at a distance, comprising at each station a moved part, stationary contacts corresponding in number to the type keys, contacts insulated from one another each electrically connected with one of said stationary contacts and movable to touch at the transmitter the corresponding type keys, all of which are electrically connected, but away from said keys at the receiver, contacts in the path of the actuated keys, a part movable over said stationary contacts, an electrically operated clutch mechanism for alternately coupling and disengaging said two parts, a clutch circuit, a contact member operated by the coupling and disengaging movements of said movable part, a line circuit closed and interrupted at the transmitter by said contact member, a line relay in said line circuit operated at the receiver for closing and breaking said clutch circuit uniformly as at the transmitter, electromagnets for each of the type keys and the finish key, solenoid-contacts, to which are moved at the receiver the movable contacts connected with the stationary contacts, a typewriting circuit including said electromagnets and said solenoid-contacts, the contact member operated by the coupling and disengaging movements of said movable part at the receiver closing and interrupting the typewriting circuit for actuating the key corresponding to that which is actuated at the transmitter.
8. Apparatus usable both as transmitter and as receiver for intercourse between typewriting machines at a distance, comprising at each station a moved part, stationary contacts corresponding in number to the type keys, contacts insulated from one another each electrically connected with one of said stationary contacts and movable to touch at the transmitter the corresponding type keys, all of which are electrically connected, but away from said keys at the receiver, contacts in the path of the actuated keys, a part movable over said stationary contacts, an electrically operated clutch mechanism for alternately coupling and disengaging said two parts, a clutch circuit, a contact member operated by the coupling and disengaging movements of said movable part, a line circuit closed and interrupted at the transmitter by said contact member, a line relay in said line circuit operated at the receiver for closing and breaking said clutch circuit uniformly as at the transmitter, electromagnets for each of the type keys and the finish key, solenoid-contacts, to which are moved at the receiver the movable contacts connected with the stationary contacts, a typewriting circuit including said electromagnets and said solenoid-contacts, the contact member operated by the coupling and disengaging movements of said movable part at the receiver closing and interrupting the typewriting circuit for actuating the key corresponding to that which is actuated at the transmitter.
9. Apparatus usable both as transmitter and as receiver for intercourse between typewriting machines at a distance, comprising at each station a moved part, stationary contacts corresponding in number to the type keys, contacts insulated from one another each electrically connected with one of said stationary contacts and movable to touch at the transmitter the corresponding type keys, all of which are electrically connected, but away from said keys at the receiver, contacts in the path of the actuated keys, a part movable over said stationary contacts, an electrically operated clutch mechanism for alternately coupling and disengaging said two parts, a clutch circuit, a contact member operated by the coupling and disengaging movements of said movable part, a line circuit closed and interrupted at the transmitter by said contact member, a line relay in said line circuit operated at the receiver for closing and breaking said clutch circuit uniformly as at the transmitter, electromagnets for each of the type keys and the finish key, solenoid-contacts, to which are moved at the receiver the movable contacts connected with the stationary contacts, a typewriting circuit including said electromagnets and said solenoid-contacts, the contact member operated by the coupling and disengaging movements of said movable part at the receiver closing and interrupting the typewriting circuit for actuating the key corresponding to that which is actuated at the transmitter.

means, a contact member operated by the coupling and disengaging movements of said movable part, a line circuit operated by said contact member, a line relay in said line circuit, the main branch of said clutch circuit including said contacts arranged in the path of the keys being closed at the transmitter by the actuated key by way of all the stationary contacts with the exception of the stationary contact corresponding to the actuated key which has left the movable contact connected with the stationary contact, the additional branch of the clutch circuit having a contact means, held at the transmitter in interrupting position by the line relay being deenergized, while at the receiver the main branch of the clutch circuit is interrupted by the movable contacts being moved away from the keys, and the additional branch is closed and interrupted uniformly as the main branch of the clutch circuit at the transmitter by the line relay operating said contact means of the additional clutch circuit branch at the receiver and means electrically operated at the receiver by said contact member for actuating the type corresponding to that which is actuated at the transmitter.

8. Apparatus usable both as transmitter and as receiver for intercourse between typewriting machines at a distance, comprising at each station a moved part, stationary contacts corresponding in number to the type keys, contacts insulated from one another each electrically connected with one of said stationary contacts and movable to touch at the transmitter the corresponding type keys, all of which are electrically connected, but away from said keys at the receiver, contacts in the path of the actuated keys, a part movable over said stationary contacts, an electrically operated clutch mechanism for alternately coupling and disengaging said two parts, a clutch circuit, a contact member operated by the coupling and disengaging movements of said movable part, a line circuit closed and interrupted at the transmitter by said contact member, a line relay in said line circuit operated at the receiver for closing and breaking said clutch circuit uniformly as at the transmitter, electromagnets for each of the type keys and the finish key, solenoid-contacts, to which are moved at the receiver the movable contacts connected with the stationary contacts, a typewriting circuit including said electromagnets and said solenoid-contacts, the contact member operated by the coupling and disengaging movements of said movable part at the receiver closing and interrupting the typewriting circuit for actuating the key corresponding to that which is actuated at the transmitter.

9. Apparatus usable both as transmitter and as receiver for intercourse between typewriting machines at a distance, comprising at each station a moved part, stationary contacts corresponding in number to the type keys, contacts insulated from one another each electrically connected with one of said stationary contacts and movable to touch at the transmitter the corresponding type keys, all of which are electrically connected, but away from said keys at the receiver, contacts in the path of the actuated keys, a part movable over said stationary contacts, an electrically operated clutch mechanism for alternately coupling and disengaging said two parts, a clutch circuit, a contact member operated by the coupling and disengaging movements of said movable part, a line circuit closed and interrupted at the transmitter by said contact member, a line relay in said line circuit operated at the receiver for closing and breaking said clutch circuit uniformly as at the transmitter, electromagnets for each of the type keys and the finish key, solenoid-contacts, to which are moved at the receiver the movable contacts connected with the stationary contacts, a typewriting circuit including said electromagnets and said solenoid-contacts, the contact member operated by the coupling and disengaging movements of said movable part at the receiver closing and interrupting the typewriting circuit for actuating the key corresponding to that which is actuated at the transmitter.

typewriting machines at a distance, comprising at each station a moved part, stationary contacts corresponding in number to the type keys, contacts, insulated from one another each electrically connected with one of said stationary contacts and movable to touch at the transmitter the corresponding type keys, all of which are electrically connected, but at the receiver away from said keys, solenoid-contacts touched at the receiver by said movable contacts, contacts in the path of the actuated keys, a part movable over said stationary contacts, an electrically operated clutch mechanism for alternately coupling and disengaging said two parts, a clutch circuit, a contact member operated by the coupling and disengaging movements of said movable part, a line circuit operated at the transmitter by said contact member, a line relay in said line circuit closing and interrupting at the receiver said clutch circuit uniformly as at the transmitter, a writing circuit having two branches, a contact means in the main branch of said writing circuit and operated by said contact member, electromagnets for each of the type keys, including with said solenoid-contacts in the main branch of the writing circuit contacts, the additional branch of the writing circuit including the electromagnet for the finish key, the solenoid-contact, to which is moved the corresponding movable contact connected with its stationary contact, a contact means released by the line relay of the receiver at its first operation and an electromagnet, which when excited by actuating the finish key at the transmitter brings said released contact means in its interrupting position, both writing circuit branches being interrupted at the transmitter by said movable contacts being moved away from said solenoid-contacts in the main branch of the writing circuit, and the contact means in the additional branch being held in the interrupting position by the line relay of the receiver at its first operation and an electromagnet, which when excited by actuating the finish key at the transmitter brings said released contact means in its interrupting position, both writing circuit branches being interrupted at the transmitter by said movable contacts being moved away from said solenoid-contacts in the main branch of the writing circuit, and the contact means in the additional branch being held in the interrupting position by the line relay.

10. Apparatus usable both as transmitter and as receiver for intercourse between typewriting machines at a distance, comprising at each station a two branch motor circuit, a moved part, stationary contacts, contacts, insulated from one another each electrically connected with one of said stationary contacts and movable to touch at the transmitter the corresponding type keys, all of which are electrically connected, but at the receiver away from said keys, solenoid-contacts touched at the receiver by said movable contacts, contacts in the path of the actuated keys, a part movable over said stationary contacts, an electrically operated clutch mechanism for alternately coupling and disengaging said two parts, a clutch circuit, a contact member operated by the coupling and disengaging movements of said movable part, a line

circuit operated at the transmitter by said contact member, a line relay in said line circuit closing and interrupting at the receiver said clutch circuit uniformly as at the transmitter, a writing circuit having two branches, a contact means in the main branch of said writing circuit and operated by said contact member, electromagnets for each of the type keys, including with said solenoid-contacts in the main branch of the writing circuit, the additional branch of the writing circuit including the electromagnet for the finish key, the solenoid contact, to which is moved the corresponding movable contact connected with its stationary contact, a contact means released by the line relay of the receiver at its first operation and an electromagnet, which when excited by actuating the finish key at the transmitter brings said released contact means in its interrupting position, both writing circuit branches being interrupted at the transmitter by said movable contacts being moved away from said solenoid-contacts in the main branch of the writing circuit, and the contact means in the additional branch being held in the interrupting position by the line relay, the contact means in the additional branch of the writing circuit being arranged at one arm of a lever, a contact on the other arm of said lever for closing at the receiver the additional branch of said motor circuit when the additional branch of said writing circuit is closed and for interrupting at the transmitter these both additional branches.

11. Apparatus usable both as transmitter and as receiver for intercourse between typewriting machines at a distance, comprising at each station a moved part, stationary contacts, corresponding in number to the type keys, a part movable over said stationary contacts, an electrically operated clutch mechanism for coupling and disengaging said two parts, a clutch circuit, a writing circuit active only at the receiver, solenoid-contacts in the writing circuit, movable contacts insulated from one another belonging to each of the type keys and the finish key, all of which type keys are connected by their common axle serving as conductor, each movable contact being connected by a conductor with one of said stationary contacts, contacts in the path of each actuated key not active at the receiver, said movable contacts being shiftable in common at the transmitter to touch the keys in their not actuated position for preparing the clutch circuit, but at the receiver to touch the solenoid-contacts of the writing circuit.

12. Apparatus usable both as transmitter and as receiver for the intercourse between typewriting machines at a distance comprising at each station a moved part, stationary contacts, corresponding in number to the type keys, a part movable over said station

ary contacts, an electrically operated clutch mechanism for coupling and disengaging said two parts, a clutch circuit, a writing circuit active only at the receiver including 5 solenoid contacts, movable contacts insulated from one another belonging to each of the type keys and the finish key all of which type keys are connected by their common axle serving as conductor, each movable contact being connected by a conductor with 10 one of said stationary contacts, contacts in the path of each actuated key not active at the receiver, said movable contacts being shiftable in common at the transmitter by 15 actuating an independent starting key to touch the keys in their not actuated position for preparing the clutch circuit, but at the receiver by actuating the finish key to touch the solenoid contacts of the writing circuit.

20 13. Apparatus usable both as transmitter and as receiver for intercourse between typewriting machines at a distance, comprising at each station an electromotor, a two branch motor circuit, the main branch of which is 25 closed at the transmitter by actuating a starting key, a part moved by said electromotor, when one of said branches is closed, stationary contacts corresponding in number to the type keys, a part movable over the 30 stationary contacts, an electrically operated clutch mechanism for coupling and disengaging said two parts, a two branch clutch circuit operating said clutch mechanism, when one of its branches is closed, contact 35 means operated at the transmitter for closing and interrupting the main branch of the clutch circuit, a contact member forming a local relay operated by the coupling and disengaging movements of said movable part, a line circuit connecting the transmitter and receiver including said local relay and a line relay, a two branch writing circuit, one branch of which belonging to the finish key including an electromagnet, said local relay closing and interrupting at the transmitter the line circuit and at the receiver the additional branch of the clutch circuit, said line relay consisting of an electromagnet with a lever bearing a contact and a means for retaining a lever belonging to the electromagnet of the writing circuit bearing two contacts, said line relay being not active at the transmitter, but its electromagnet being excited at the receiver by the movements of said contact member at the transmitter, whereby its lever is attracted and released, whose contact closes and interrupts the additional clutch circuit branch 100 uniformly as the main branch is operated at the transmitter, the line relay lever when at first attracted releasing the lever of the electromagnet of the writing circuit branch, whose one contact closes the additional motor circuit branch while the other contact prepares the additional writing circuit branch, which when closed by actuating the finish key at the transmitter excites its electromagnet attracts its lever and interrupts the additional motor circuit branch and the additional writing circuit branch at the receiver, a switch in the line circuit moved in opposite directions by actuating the starting 105 and finish keys, a contact piece of the main branch of the motor circuit on said switch, a contact means half conducting and half non-conducting on said switch, adjacent elastic contacts in the line circuit and the main branch of the clutch circuit moved 110

branch, which when closed by actuating the finish key at the transmitter excites its electromagnet attracts its lever and interrupts the additional motor circuit branch and the additional writing circuit branch at the receiver.

14. Apparatus usable both as transmitter and as receiver for intercourse between typewriting machines at a distance, comprising at each station an electromotor, a two branch motor circuit, the main branch of which is closed at the transmitter by actuating a starting key, a part moved by said electromotor, when one of said branches is closed, stationary contacts corresponding in number to the type keys, a part movable over the stationary contacts, an electrically operated clutch mechanism for coupling and disengaging said two parts, a two branch clutch circuit operating said clutch mechanism, when one of its branches is closed, contact means operated at the transmitter for closing and interrupting the main branch of the clutch circuit, a contact member forming a local relay operated by the coupling and disengaging movements of said movable part, a line circuit connecting the transmitter and receiver including said local relay and a line relay, a two branch writing circuit, one branch of which belonging to the finish key including an electromagnet, said local relay closing and interrupting at the transmitter the line circuit and at the receiver the additional branch of the clutch circuit, said line relay consisting of an electromagnet with a lever bearing a contact and a means for retaining a lever belonging to the electromagnet of the writing circuit bearing two contacts, said line relay being not active at the transmitter, but its electromagnet being excited at the receiver by the movements of said contact member at the transmitter, whereby its lever is attracted and released, whose contact closes and interrupts the additional clutch circuit branch uniformly as the main branch is operated at the transmitter, the line relay lever when at first attracted releasing the lever of the electromagnet of the writing circuit branch, whose one contact closes the additional motor circuit branch while the other contact prepares the additional writing circuit branch, which when closed by actuating the finish key at the transmitter excites its electromagnet attracts its lever and interrupts the additional motor circuit branch and the additional writing circuit branch at the receiver, a switch in the line circuit moved in opposite directions by actuating the starting and finish keys, a contact piece of the main branch of the motor circuit on said switch, a contact means half conducting and half non-conducting on said switch, adjacent elastic contacts in the line circuit and the main branch of the clutch circuit moved

5 apart by the entering of said half conducting contact means when the switch is moved by the actuated finish key to close the line circuit and to interrupt the main clutch circuit, the contact piece on the switch being at the same time moved apart to interrupt the main branch of the motor circuit for preparing the station as receiver, while by 10 actuating the starting key at the transmitter 10 the contact-piece on the switch closes the main branch of the motor circuit and the half conducting contact means releases the elastic contacts to interrupt the line circuit and to close the main branch of the clutch circuit, the actuating of the finish or starting key preparing at the same time the writing circuit at the receiver or interrupting it at the transmitter.

15. Apparatus usable both as transmitter 20 and as receiver for intercourse between type-writing machines at a distance, comprising at each station a moved part, stationary con-

25 facts, a part movable over the stationary contacts, an electrically operated means for coupling and disengaging said two parts, a clutch circuit, a contact member moved by the coupling and disengaging movements of said movable part, a line circuit connecting the transmitter and receiver, a line relay in said line circuit operated at the receiver by 30 said contact member at the transmitter, the contacts actuated by said contact member being formed as adjustable sliding or brush-contacts for the purpose of obtaining at both stations an equal time of the connection of the movable part with the moved part.

35 In testimony, that I claim the foregoing as my invention, I have signed my name in presence of two subscribing witnesses.

H. EMANUEL M. SCHNÜRER.
